LAMINATED WOODEN BOWLING PIN

Russell C. Diehl, Baltimore, Md.

Application April 26, 1946, Serial No. 665,057

4 Claims. (Cl. 273—82)

1

This invention relates to the construction of bowling pins, such as duckpins, tenpins, barrel pins, candlepins, and the like for use in games in which they are subjected to violent impact from bowling balls and from striking other pins and portions of the bowling alley where used.

The bowling pins now in general use are conventionally made by turning in a lathe from a solid piece of maple. The region of greatest wear of such a pin occurs on the base portion at a level with the center of the bowling ball used. In duckpins, this region is also the region of maximum circumference of the pin, which increases the wear on this particular region due to striking other pins and portions of the alley. When subjected to such wear, a conventional bowling pin soon commences to flake and chip in this region, changing the weight and balance characteristics of the pin as well as altering its physical dimensions.

It has been observed that the greatest wear on such a pin occurs at two generally opposite portions of this region, coinciding with the inevitable areas of slab grain of the conventional pin. This is due to the fact that the slab grain of wood does not have as much resistance to wear from abrasion or impact as does edge grain.

Accordingly, it is proposed in this invention to obviate the above-mentioned difficulty by an improved bowling pin construction that will have no large areas of slab grain exposed at the base portion thereof and that may be simply and easily constructed from short pieces of maple.

Other objects and the nature and scope of the invention will be apparent to one skilled in the art from a study of the appended description, made in conjunction with the drawings, in which:

Fig. 1 is an elevational view, partly in section, of a duckpin embodying my invention.

Fig. 2 is a second elevation of the pin shown in Fig. 1 taken at a 90° angle thereto.

Fig. 3 is a top plan view of the pin shown in Fig. 1, and

Fig. 4 is a cross sectional view taken on the line 4—4 of Fig. 1.

Referring to Fig. 1, my improved form of bowling pin is formed from a blank 10 shown in broken line in Figs. 1 and 3 and formed of a central piece 11 and shorter side pieces 12 secured to the sides of piece 11 adjacent one end thereof, thus forming the blank 10 which is of approximately square cross section in the composite portion. Each of the side pieces 12 preferably consists of three separate pieces 13, 14 and 15 secured together but may be formed of any number without departing

2

from the scope of this invention. The individual pieces forming the blank 10 are preferably united with a surface bonding agent such as glue or cement, the resin glues being desirable for this purpose.

In order to obtain the maximum wear from the bowling pin, the central piece 11 is selected from a piece of wood, customarily maple, having the grain or growth rings running generally parallel with the width thereof as shown in Fig. 4. The direction of the grain of a piece of wood is determined by the method of sawing the log from which it is cut, as is well known. Hence, the central piece 11 is selected from a board that has been cut with the grain running in that manner.

The side pieces 12 are selected from pieces of wood in which the grain runs generally perpendicular to the broader face, so that the blank 10, when assembled will consist of the central piece 11 having its grain running generally across the central portion of the blank 10 and the side pieces 12 having their grain running generally perpendicular to the grain of the central piece 11.

After assembly, the blank 10 may be turned in a lathe to produce the bowling pin. The turning of the composite blank 10 to produce the finished pin is similar to the operation of turning the conventional pin and hence need not be described in detail. After the pin is turned, it may be finished in the customary manner with clear or white lacquer or varnish.

The completed pin presents, in the base portion thereof, a maximum of edge grain consistent with easy fabrication of the blank 10. All intersecting surfaces of the pieces forming the blank 10 meet at right angles, thus simplifying the cutting and assembly of the pieces forming the blank.

If desired, the pieces 13 and 15 of blank 10 may be selected from strips of wood having the grain slightly inclined to the grain of piece 14 so that the grain of these pieces, when in place forming the blank 10, will be generally parallel to radii 45 through the midportions of these pieces. This construction of blank 10 will increase slightly the wearing ability of the finished pin due to the fact that the growth rings of pieces 13 and 15 at the finished surface of the pin will be a little closer together.

While the pin shown and described is a duckpin, it is contemplated that other types of bowling pins may be made in the same manner and the invention is not limited to duckpins alone.

It will be obvious to those skilled in the art

that my invention obviates the necessity and expense of manufacturing pins from large blocks of kiln dried maple and utilizes scraps of wood that would otherwise be scrapped, or smaller sizes of commercial lumber which is always more readily available and less expensive. In addition, by the use of several pieces to form the pin, a pin having a more uniform weight is obtained since the weight is a function of the densities of the individual pieces. This feature is of particular importance in the manufacture of tenpins in which weight of the finished pin is of primary importance. The most important accomplishment of this method of construction, however, is the greatly increased durability and longer life of the pin, due to its ability to withstand repeated violent impact of the balls without splitting the pin, which is a common and frequent occurrence with a pin made from a single unitary block of wood. The pin also maintains its original shape without excessive flaking, scaling or chunking out which is a frequent occurrence with the conventional pin having two slab-grain sides.

Certain deviations from the construction shown and described herein may be made without departing from the scope of the invention, which is defined by the following claims.

I claim:

1. A wooden bowling pin comprising a transverse central section having two parallel sides, 30 extending between opposite sides of the pin and forming the head, neck, and a portion of the base of said pin, the grain of said section running generally parallel to said parallel sides, and a plurality of side sections secured to each of said parallel sides and forming the remainder of the base thereof, the grain of said side sections running generally perpendicular to the grain of said central section.

2. A wooden bowling pin comprising a transverse central section having two parallel sides, 40 extending between opposite sides of the pin and forming the head, neck, and a portion of the base of said pin, the grain of said section running generally parallel to said parallel sides, and 45

a side section secured to each of said parallel sides and forming the remainder of the base thereof, the grain of said side sections running generally perpendicular to the grain of said central section.

3. A wooden bowling pin comprising a transverse central section extending for the diameter of said pin and having its grain substantially parallel to said diameter, and three side sections secured to each side of said central section, the middle side sections having grain running generally perpendicular to said central section, and the end side sections having grain slightly inclined to the grain of said middle side sections.

15 4. A wooden bowling pin comprising a transverse central section having two substantially parallel sides, extending between opposite sides of the pin and forming the head, neck, and a portion of the base of said pin, the grain of said section running generally parallel to said parallel sides, and a side section secured to each of said parallel sides and forming the remainder of the base thereof, the grain of said side sections running generally perpendicular to the grain of the central section, whereby edge grain is provided about the periphery of the pin base.
